Patented May 14, 1918.

Inventor

Edward Stanley Klein

By Attorney

UNITED STATES PATENT OFFICE.

EDWARD STANLEY KLEIN, OF MERIDEN, CONNECTICUT.

DESIGN FOR A BURIAL-CASKET HANDLE.

52,043.

Specification for Design.

Patented May 14, 1918.

Application filed March 15, 1918. Serial No. 222,742. Term of patent 7 years.

To all whom it may concern:

Be it known that I, EDWARD STANLEY KLEIN, a citizen of the United States, residing at the city of Meriden, county of New Haven, and State of Connecticut, have invented a new, original, and ornamental Design for a Burial-Casket Handle, of which the following is a specification, reference

being had to the accompanying drawing, forming part thereof.

The figure is a side elevation of a burial casket handle showing my new design.

I claim:—

The ornamental design for a burial casket handle, as shown.

EDWARD STANLEY KLEIN.
